UNITED STATES PATENT OFFICE.

ROBERT B. McCANN, OF CHICAGO, ILLINOIS, ASSIGNOR OF ONE-FOURTH TO WILLIAM DICKERSON, OF CHICAGO, ILLINOIS.

AEROPLANE.

1,240,070.

Specification of Letters Patent. Patented Sept. 11, 1917.

Application filed April 20, 1917. Serial No. 163,431.

To all whom it may concern.

Be it known that I, ROBERT B. McCANN, a citizen of the United States, residing at Chicago, in the county of Cook and State of Illinois, have invented certain new and useful Improvements in Aeroplanes; and I do hereby declare the following to be a full, clear, and exact description of the invention, such as will enable others skilled in the art 10 to which it appertains to make and use the same.

The invention relates to improvements in aeroplanes.

The object of the present invention is to 15 improve the construction of aeroplanes and to provide a simple, practical and efficient aeroplane of the biplane type equipped with front and rear sets of biplanes and provided with means for enabling a plurality of 20 passengers to be conveniently carried and capable of enabling the necessary power to be readily developed.

A further object of the invention is to provide a double biplane provided at each 25 set of biplanes with opposite pairs of propellers and having a central engine emplacement with respect to the biplane.

With these and other objects in view, the invention consists in the construction and 30 novel combination of parts hereinafter fully described, illustrated in the accompanying drawings and pointed out in the claims hereto appended; it being understood that various changes in the form, proportion, 35 size and minor details of construction, within the scope of the claims, may be resorted to without departing from the spirit or sacrificing any of the advantages of the invention.

40 In the drawings:

Figure 1 is a side elevation of the double biplane airship constructed in accordance with this invention.

Fig. 2 is a front elevation of the same.

45 Fig. 3 is a horizontal sectional view.

Fig. 4 is a detail view illustrating the arrangement of the hydroplanes or floats when it is desired to substitute the same for wheels to adapt the machine for hydroplaning.

50 Like numerals of reference designate corresponding parts in the several figures of the drawings.

In the accompanying drawings, in which is illustrated the preferred embodiment of 55 the invention, the aeroplane comprises in its

construction a frame designed to be constructed of any suitable material and composed of tapered front and rear sections 1 and 2 located respectively in advance and in rear of front and rear upper and lower 60 supporting planes 3 and 4, and an intermediate longitudinally disposed substantially oblong connecting portion located between the front and rear upper and lower supporting planes 3 and 4, as clearly illustrated in Fig. 1 of the drawings. The frame is equipped with a front wheel 6 and side wheels 7 and 8 arranged in pairs and located beneath the front and rear upper and lower supporting planes and mounted on suitable 70 axles 9 and 10 and the said axles are connected with the frame by means of standards 11 and suitable braces 12 and 13 arranged at an inclination and located in advance and in rear of the axles of the front 75 and rear side wheels. The side wheels are located centrally beneath the end portions of the lower supporting plane and the aeroplane is provided with a central longitudinal bar or member 15 extending rearwardly 80 from the apex of the tapered front portion of the frame to the front axle 9 and connected with the frame by suitable braces. The axles may be braced in any other desired manner and instead of employing 85 wheels the frame may be equipped with hydroplanes or floats 17, as illustrated in Fig. 4 of the drawings to adapt the aeroplane for hydroplaning. The front tapered section 1 extends downwardly and forwardly at an inclination and it is provided with a space or compartment 18 for the accommodation of the aviator guiding the aeroplane. The rear tapered section 2 has a substantially uniform taper rearwardly 90 and it carries a rudder plane 19, which may be of any desired construction and any suitable equipment may be employed for steering the aeroplane.

The intermediate oblong connecting portion 5, which is located between the two sets of supporting planes, is provided at the lower portion with opposite rows of seats 20 for the accommodation of passengers and the machine may be made of any desired 105 size to provide the necessary carrying capacity. The front portion of the intermediate section 5 is adapted to afford a convenient position for a fuel tank 21, and the said intermediate connecting passenger car- 110

rying section is braced at the bottom by longitudinal truss rods 22 consisting of inclined terminal portions and intermediate horizontal portions and provided with central adjusting means 23 preferably consisting of turn buckles, as shown. The longitudinal truss rods are spaced from the intermediate section at the bottom thereof by transverse I-beams 24, which form struts 10 for the truss rods and provide with the same a truss structure of great strength and durability and at the same time possessing the requisite lightness. The front, rear and intermediate sections of the frame are preferably braced as shown, but the bracing means may, of course, be varied to secure the desired strength.

The aeroplane is equipped at the front and rear of the terminal laterally projecting portions of the upper and lower supporting frames with propellers 25 and 26 arranged in pairs and mounted on the front and rear ends of longitudinally disposed shafts 27 and 28. The shafts 27 and 28 are connected 25 by sprocket gearing 29 and 30 with engines or motors 31 and 32, which are of ordinary type of internal combustion engine. The engines are centrally arranged with respect to the supporting planes which are 30 adapted to afford ample power for propelling the machine.

The front and rear upper and lower supporting planes are arched as shown, and the side wheels have their axles located centrally 35 of the terminal portions of the planes, that is midway between the front and rear edges thereof, and the inclined braces 12 and 13 extend to the frame from the axle, having their upper portions connected with the 40 frame adjacent to the front and rear edges of the lower supporting planes as shown. By this arrangement the rigid structure of the frame work is produced.

The aeroplane is adapted to be provided 45 with the usual equipment of operating means and stabilizing and equalizing devices may, of course, be employed.

The aeroplane may also be provided between the pairs of upper and lower supporting planes with centrally arranged transversely disposed planes 33 located midway 50 between the upper and lower supporting planes and mounted on vertical standards 34 and braced by inclined upper and lower 55 braces 35. The central planes 33 are of a width less than the upper and lower supporting planes and are curved in substantial parallelism with the said planes.

The central or intermediate connecting 60 portion of the main frame forms a compartment and is provided with a platform 36 and the seats are located at opposite sides of the same, as clearly shown in Fig. 3 of the drawings. The compartment or space 65 for the accommodation of the passengers

may be made of any desired size, and the front and rear supporting planes will be of corresponding areas to sustain the aeroplane. The walls of the compartment 36 are preferably composed of vertical standards 37 70 and top and horizontal connecting members, crossed inclined braces 38 being preferably arranged in the spaces between the vertical standards. The braces 38 extend from the top to the bottom of the standards, and the 75 front and rear sections and the front and rear supporting planes are preferably braced in a similar manner by crossed inclined bracing rods mounted between vertical supports.

What is claimed is:

1. An aeroplane of the class described including a frame having front and rear tapered sections and an intermediate connecting section, the front tapered section being inclined downwardly and forwardly, 85 and front and rear upper and lower transversely disposed laterally projecting supporting planes located at the adjacent ends of the sections and arched longitudinally of the machine.

2. An aeroplane of the class described including a frame comprising front and rear tapered sections, and an intermediate oblong connecting section, upper and lower front and rear supporting planes located between 95 the said sections of the frame and extending laterally therefrom at opposite sides thereof, supporting devices located at the front end of the front section below the terminal portions of the lower supporting plane, a lower 100 central longitudinal frame member extending from the front end of the tapered front section to a point below and centrally of the front supporting planes and connected with the supporting means thereof, and braces 105 connecting the frame member with the frame.

3. An aeroplane of the class described including a frame provided with spaced upper and lower front and rear transversely disposed laterally projecting supporting planes, longitudinally disposed shafts located at opposite sides of the frame and mounted between the upper and lower front and rear supporting planes and extending across the same, front and rear propellers mounted on the front and rear ends of the said shafts and arranged in pairs at opposite sides of the machine at the front and rear portions thereof, centrally arranged engines mounted 115 on the frame and also located between the supporting planes, and gearing for connecting the engines with the said shafts.

4. An aeroplane of the class described including a frame having front, rear and intermediate sections, the intermediate section being provided with means for the accommodation of passengers, upper and lower transversely disposed supporting planes arranged in pairs at the front and 130

rear portions of the frame and located between the said sections, longitudinal truss rods arranged beneath the central or intermediate sections and having adjusting means, and transverse struts interposed between the truss rods and the frame.

5. An aeroplane of the class described including front, rear and intermediate sections, front and rear upper and lower transversely disposed supporting planes arranged in pairs, vertical standards centrally arranged between the upper and lower supporting planes, centrally arranged planes mounted on the standards and located between the upper and lower supporting planes, and braces extending from the standards to the centrally arranged planes.

10. An aeroplane of the class described including front, rear and intermediate sec-

tions, front and rear upper and lower transversely disposed supporting planes arranged in pairs, vertical standards centrally arranged between the upper and lower supporting planes, centrally arranged planes mounted on the standards and located between the upper and lower supporting planes, and braces extending from the standards to the centrally arranged planes, said supporting planes and centrally arranged planes being curved in parallelism and presenting upper convex faces and lower concave faces.

15. In testimony whereof I affix my signature in presence of two witnesses.

ROBERT B. McCANN.
